MILLING MACHINE RAM SADDLE-WEDGE
LOCK

Charles Tree, Racine, Wis.

Application August 18, 1952, Serial No. 304,959

2 Claims. (Cl. 90—17)

1

This invention appertains to metal working machines and more particularly to a novel locking means for the rotatable supporting elements in a milling machine.

A primary object of my present invention is to provide novel wedge means for quickly and easily locking or releasing a rotatable element of the milling machine to its respective support, for example, the locking of the ram saddle to the column and/or the locking of the over arm to the sliding ram.

Another object of my invention is to provide a novel lock wedge and a lock thrust bar both of which slide on a cross brace and supporting bar of the column and both of which bear against the respective portions of a ring segment to firmly force the same against the adjacent surface of the ram saddle and the column to lock said ram saddle against rotation.

Still another object of my invention is to provide an operating adjusting screw for the sliding wedge lock which projects outwardly from the column or standard of the milling machine and which is provided with a polygonal terminal for receiving a hand crank or wrench when it is desired to rotate the same.

A more specific object of my invention is to provide an annular groove in the upper and lower inner peripheries of the frame column and the ram saddle respectfully, in such a manner that the adjacent abutting surface of the column and saddle cooperate to form an annular projecting V, the ring segment of the novel locking means is provided with a mating annular V groove in its outer periphery which is of a size and configuration to receive the projecting V and which, by means of my novel sliding wedge lock and lock thrust bar, may be tightened against the respective portions of the column and ram saddle to lock them against relative movement.

A still further object is to provide a novel locking means for a rotatable turret ram saddle which is simple in construction, reliable in its operation and not liable to get out of order.

With these and other objects in view, and to the end of attaining any other advantage hereinafter appearing, this invention consists in certain features of construction, combination and arrangement of parts, hereinafter described, pointed out in the claims and illustrated in the accompanying drawings, in which drawings:

Figure 1 is a side elevational view illustrating a milling machine in which the ram saddle is mounted on the column in accordance with my present invention;

2

Figure 2 is a longitudinal horizontal sectional view taken through the ram saddle on the line 2—2 of Figure 1, looking in the direction of the arrows and illustrating in top plan my novel wedge locking means, certain parts being broken away to illustrate further details of construction;

Figure 3 is a fragmentary longitudinal vertical sectional view through my novel locking means and its associated elements taken on the line 3—3 of Figure 2 and looking in the direction of the arrows; and

Figure 4 is a fragmentary transverse vertical section taken on the line 4—4 of Figure 3 and looking in the direction of the arrows.

Referring now to the drawings in detail, wherein similar reference characters designate corresponding parts throughout the several views, the letter "M" generally indicates one type of my improved milling machine and referring in particular to Figure 1 of the drawings, the same includes broadly the universal milling head 10 which is mounted on an over arm 11 so that the head 10 may be moved or tilted in a longitudinal, vertical, arcuate path by rotating the projecting stud or polygonal terminal 12. The overarm 11 is, in turn, rotatably mounted to the ram 13 so that by applying a hand crank or wrench to the polygonal terminal of the projecting stud 14 and turning the same in one direction, the overarm may be loosened and the milling head 10 tilted or moved in a transverse vertical arcuate path at right angles to its arcuate movement in relation to the overarm 11.

The ram 13 is slidably mounted in the saddle 15 by the dove tail arrangement 16 so that the milling head may be moved backward and forward longitudinally of the machine by sliding the ram as desired. The ram 13 may be locked to the saddle 15 by means of the two bolts 16 and by the tightening of the polygonal terminal of the projecting stud 17. The saddle 15 is, in turn, rotatably mounted on the column or frame standard 18 and this allows the milling head 10 to be moved in a horizontal arcuate path transversely of the machine. The column or frame standard 18 has formed on its forward end the male portion 19 of a dove tailed arrangement to which the work table (not shown) is slidably secured for vertical movement relative to the machine milling head 10, as more fully described in my co-pending application, Serial Number 285,180, filed April 30, 1952, entitled "Gib for Knee of Milling Machine."

55 While all the above described elements form no

particular part of my present invention and my novel wedge locking means may be utilized with any type of milling machine, in practicing my invention, I prefer to apply the same to the general type of milling machine embodying my milling head shown and described in my prior Patent No. 2,491,940, issued to me on December 20, 1949.

While the present invention may be used to effectively lock any rotatable element or turret means to its respective support, it has proven particularly useful in locking or releasing both the rotatable ram saddle 15 and the rotatable overarm 11 to their respective support elements. However, for the purpose of illustration I have shown and described my novel wedge locking means with relation to the ram saddle 15 and its supporting column or standard 18.

The ram saddle 15 and the column 18 are cast hollow and in accordance with the preferred embodiment of my invention, the column 18, adjacent the upper end 10, is provided with a transversely extending brace and supporting bar 20, the center of which has a vertical bore 21 therethrough. Although not necessary, I prefer to form one end of the brace bar 20 with a recessed portion 22 to provide a guide and support for the saddle wedge lock 23.

The ram saddle 15 is, in turn, provided with a centrally positioned depending spindle or stub axle 24, the lower end of which extends into and is snugly received in the bore 21. The respective surface of the stub axle 24 and bore 21 are highly polished so that the ram saddle 15 may be easily turned and swung in any direction on its supporting column 18.

The extreme upper end 25 of the column 18 has formed in its inner periphery, a sharp angled annular groove of a size and configuration to provide an upwardly angularly extending surface 26; and the extreme lower end 27 of the ram saddle 15 has formed in its periphery, a similarly shaped annular groove which provides a complementary downwardly extending surface 28 and, it is to be noted that when the saddle is in its operative position on the column 18 as shown, with their respective end surfaces 29 in abutting relation, that the two corresponding angular surfaces 26 and 28 of the grooves co-operate to form an annular projecting V 30. Snugly fitting against the surfaces 26 and 28 and the projecting V 30 is a segment ring 31. This segment ring 31 is formed with an opened throat 32 at one end, the opposed surfaces 33 of which converge outwardly towards one another as shown. The outer annular periphery of the ring segment 31 is formed with a correspondingly shaped V groove which snugly receives the projecting V 30. If desired, the ring segment 31 may be formed in one piece and be of a somewhat resilient material. However, due to the relatively heavy work and strength required, I prefer to cast the ring segment in three portions. As illustrated, more particularly in Figure 2 of the drawing, the ring segment 31 includes a short center portion 34, and two equal side portions 35 and 36, which are spaced at their outer opposed ends 33, as previously described, to form the throat 32. However, the inner ends 37 of the side portions 35 and 36 fit tightly against the respective ends of the center portion 34. Slidably mounted on the upper surface of the brace bar 20 is a lock thrust bar 38 having formed on one end thereof a stub nose 39 which abuts the inner periphery of the center ring portion 34.

The lock thrust bar 38 is also formed with an enlarged centrally positioned opening or slot 39' through which the spindle or stub axle 24 of the saddle 15 passes. The opening 39' is sufficiently large so as to permit free movement of the lock thrust bar 38.

The other end of the lock thrust bar 38 is formed with a short projecting block portion 40 which is provided with a central bearing or circular recess 41. Rotatably received in the bearing 41 is the inner end 42 of the wedge adjusting screw 43. This adjusting screw is threadedly received in the saddle wedge lock 23 and its outer end 44 projects outwardly from the surface of the standard 18 and is formed as a polygonal terminal receiving a wrench or hand crank (not shown). By rotating the hand crank, the adjusting screw 43 will cause the wedge lock to slide in the guide recess 22 of the brace bar 20.

From the above it should be readily apparent that by rotating the adjusting screw 43 in one direction, so as to move the wedge lock 23 outwardly in a direction away from the center of the bar 20; that the wedge surface 45 of the wedge lock 23 will move into the converging throat 32 and will push or force the portions 35 and 36 of the ring segment 31 into a firm locking engagement with the respective portions of the ram saddle 15 and the column or standard 18. At the same time, the stub nose 39 of the lock thrust bar 38, is moved firmly against the portion 34 of the ring segment 31 and forces the same into intimate engagement with the projecting V 30 and the respective surfaces 26 and 28 of the ram saddle 15 and the standard or column 18. The ram saddle 15 will now be locked against rotative movement with relation to its supporting column 18.

However, by rotating the adjusting screw 43 in the opposite direction, the locking wedge 23 will be withdrawn from the throat 32 and the pressure exerted through the ring portions 34, 35, and 36 against the respective portions of the column and ram saddle will be relieved and the turret ram saddle 15 may then be turned or swung on the column 18 about its spindle or stub axle 24 to adjust the milling head 10 in any position along a horizontal transverse arcuate path. When the correct position of the milling head 10 has been ascertained, the adjusting screw 43 is again turned to tightly force the three portions 34, 35, and 36 of the ring segment 31 into intimate engagement with the ram saddle 15 and standard 18 so that they will be firmly locked together.

From the foregoing it is believed that the features and advantages of the invention will be readily apparent to those skilled in the art and it will, of course, be understood that changes in form, proportions, and minor details of construction may be resorted to without departing from the spirit or scope of the appended claims.

I claim:

1. The combination with a milling machine of the type having a hollow column and a hollow rotatable ram saddle mounted thereon, of a locking and releasing device for locking and releasing the ram saddle in relation to the column, the upper inner end of said hollow column having an annular groove formed in its inner peripheral surface of a size and configuration to provide an upward and angularly extending surface, the lower inner end of the hollow rotatable ram saddle having formed in its inner peripheral surface a similarly shaped annular groove to provide a downwardly extending angular surface, said respective angular surfaces cooperating to

form an annular projecting V, a three part ring segment including two equal side segments and a relatively smaller center segment, said side segments being spaced at one end to form an open throat, a V notch formed in the outer peripheral surface of said ring segments, a cross brace bar on said column adjacent the upper end thereof and below said annular groove, a wedge lock slidably mounted on said bar adjacent said open throat of the ring segment, a lock thrust bar supported by said cross bar having one end in abutting relation with the lock wedge and the opposite end abutting said center ring segment, an adjusting screw supported by said column and threadedly received in said wedge lock for 10 sliding it into and out of said entrance throat, whereby, turning of the adjusting screw in one direction will move the wedge lock into the en-

trance throat and firmly press the lock thrust bar against the center segment of the ring segment to firmly lock the column and ram saddle against relative movement.

2. A locking and releasing device for a milling machine as set forth in claim 1 in which the column brace bar has a recess formed at one end to receive and guide the lower end of the wedge lock.

CHARLES TREE.
